US0D1024052S

(12) **United States Design Patent** (10) **Patent No.:** **US D1,024,052 S**
(45) **Date of Patent:** **** Apr. 23, 2024**

(54) **NOTEBOOK COMPUTER**

(71) Applicant: **Acer Incorporated**, New Taipei (TW)

(72) Inventors: **Cheng-Han Lin**, New Taipei (TW);
Pao-Ching Huang, New Taipei (TW)

(73) Assignee: **Acer Incorporated**, New Taipei (TW)

(**) Term: **15 Years**

(21) Appl. No.: **29/826,489**

(22) Filed: **Feb. 14, 2022**

(30) **Foreign Application Priority Data**

Sep. 14, 2021 (TW) 110304935

(51) **LOC (14) Cl.** **14-02**

CLAIM

The ornamental design for a notebook computer, as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the notebook computer in a closed state; and,

FIG. 10 is another perspective view thereof showing the notebook computer in a closed state.

(Continued)

The dashed broken lines illustrate portions of the notebook computer that form no part of the claimed design.

1 Claim, 9 Drawing Sheets
